BACKGROUND OF THE INVENTION

The disclosure generally relates to compounds of formula I, including their salts, as well as compositions and methods of using the compounds. The compounds are ligands, agonists and partial agonists for the mGluR5 receptor and may be useful for the treatment of various disorders of the central nervous system.

Glutamate is the major excitatory neurotransmitter in the mammalian brain, playing an important physiological role in a wide variety of processes. Glutamatergic neurotransmission is predominantly mediated through activation of cell surface receptors including ligand-gated ion channels (ionotropic receptors) and metabotropic glutamate G protein coupled receptors (mGluRs). The metabotropic glutamate receptor family is comprised of 8 family members that are part of the family 3 GPCR superfamily. These receptors are further subdivided into Group I (mGluR 1, 5), Group II (mGluR 2, 3) and Group III (mGluR 4, 6, 7, 8) based upon sequence homology, receptor signaling, and pharmacology.

The Group I receptor mGluR5 has emerged as a target of potential therapeutic utility in a number of disease states (see: Rodriguez, A. L., et al. Current Opinion in Drug Discovery & Development (2007), 10(6), 715-722. and Chen, Y., et al. Drugs of the Future (2008), 33(4), 355-360. and Lindsley, C. W., et al. Current Opinion in Drug Discovery & Development (2009), 12(4), 446-457). The receptor is expressed broadly throughout the CNS with predominant post-synaptic localization, although pre-synaptic expression is also present. mGluR5 is a G_q-coupled receptor activating phospholipase C and elevating intracellular calcium levels, leading to activation of downstream signaling molecules. Many studies have demonstrated a role for the receptor in regulating NMDA receptor activity as well as synaptic plasticity, suggesting this receptor plays a key role in glutamatergic signal transduction.

Based on the expression pattern and functional role of mGluR5, this receptor has emerged as an important target for drug discovery in a number of therapeutic indications. Evaluation of genetically modified mice lacking mGluR5 as well as compounds that modulate receptor function suggest ligands that modulate mGluR5 receptor function have therapeutic utility in CNS and peripheral disease states including, but not limited to, schizophrenia (see: Conn, P. J., et al. Trends in Pharmacological Sciences (2009), 30(1), 25-31; and Kanuma, K., et al. Recent Patents on CNS Drug Discovery (2010), 5(1), 23-34), cognitive impairment (see: Simonyi, A., et al. European Journal of Pharmacology (2010), 639(1-3), 17-25), Alzheimer's disease, Parkinson's

disease (see: Johnson, K. A., et al. CNS & Neurological Disorders Drug Targets (2009), 8(6), 475-491), Parkinson's disease levodopa-induced dyskinesia (see: Rylander, D., et al. Neurobiology of Disease (2010), 39(3), 352-361), addiction (see: Olive, M. F. Current Drug Abuse Reviews (2009), 2(1), 83-98), anxiety (see: Jacob, W., et al. Neuropharmacology (2009), 57(2), 97-108), depression (see: Witkin, J. M., et al. CNS & Neurological Disorders: Drug Targets (2007), 6(2), 87-100), psychosis, epilepsy, Fragile X (see: Dolen, G., et al. Journal of Physiology (Oxford, United Kingdom) (2008), 586(6), 1503-1508), gastroesophageal reflux disease (see: Boeckxstaens, G. E. Expert Opinion on Emerging Drugs (2009), 14(3), 481-491), migraine (see: Marin, J., et al. Expert Opinion on Investigational Drugs (2010), 19(4), 555-561), pain, and others.

The invention provides technical advantages, for example, the compounds are novel and are ligands for the mGluR receptor and may be useful for the treatment of various disorders of the central nervous system. Additionally, the compounds provide advantages for pharmaceutical uses, for example, with regard to one or more of their mechanism of action, binding, inhibition efficacy, target selectivity, solubility, safety profiles, or bioavailability.

Biological Methods

mGluR5 FLIPR Assay.

HEK293 (ZF) cells stably transfected with human GluR5A (pIRES neo) and the rat glutamate-aspartate transporter (GLAST; pIRES puro) are grown in a monolayer culture at 37° C. in 5% CO₂ and fed with Minimum Essential

Medium (MEM) supplemented with 10% dialysed fetal bovine serum. 24 hours prior to assay, cells are enzymatically dissociated from the culture flask (Trypsin, 0.25%), spun down (1000 rpm, 3 min), resuspended, and plated on Greiner black clear bottomed PDL-coated 384-well plates at 5 a density of 30 thousand cells/well. On the day of the experiment, media is removed from the cell plates and replaced with Molecular Devices Calcium 4 microfluorometric Ca⁺⁺ sensitive dye in assay buffer (HBSS; Gibco #14025+20 mM HEPES and 250 uM probenacid). Plates are 10 incubated in dye at 37° C. in 5% CO₂ for 60 minutes prior to delivery of test compounds in assay buffer. Test compounds are incubated with cells in the presence of dye for 10 minutes prior to being read on the FLIPR platform (Molecular Devices). A Ca⁺⁺ signal is induced in the assay plates via 15 the delivery of an ~EC₁₀ concentration of the endogenous agonist 1-glutamate; images are acquired at 1 Hz for 100 seconds post-delivery of agonist stimulus. Positive modulator activity (i.e. the ability of test compounds to increase the 20 Ca⁺⁺ response to a sub-maximal concentration of agonist) is normalized to a saturating concentration of a known mGluR5 PAM run in each assay plate. An EC₅₀ concentration of test compounds is derived from 4-parameter logistic 25 curve fits of transformed fluorescence data via proprietary software suite.

"Patient" means a person suitable for therapy as understood by practitioners in the field of affective disorders and neurodegenerative disorders.

"Treatment," "therapy," and related terms are used as understood by practitioners in the field of neurological and psychiatric disorders.

The compounds of this invention are generally given as pharmaceutical compositions comprised of a therapeutically effective amount of a compound or its pharmaceutically acceptable salt and a pharmaceutically acceptable carrier and may contain conventional excipients. Pharmaceutically acceptable carriers are those conventionally known carriers having acceptable safety profiles. Compositions encompass all common solid and liquid forms including for example capsules, tablets, lozenges, and powders as well as liquid suspensions, syrups, elixers, and solutions. Compositions are made using common formulation techniques, and conventional excipients (such as binding and wetting agents) and vehicles (such as water and alcohols) are generally used for compositions. See, for example, Remington's Pharmaceutical Sciences, Mack Publishing Company, Easton, Pa., 17th edition, 1985.

Solid compositions are normally formulated in dosage units and compositions providing from about 1 to 1000 mg of the active ingredient per dose are preferred. Some examples of dosages are 1 mg, 10 mg, 100 mg, 250 mg, 500 mg, and 1000 mg. Generally, other agents will be present in a unit range similar to agents of that class used clinically. Typically, this is 0.25-1000 mg/unit.

Liquid compositions are usually in dosage unit ranges. Generally, the liquid composition will be in a unit dosage range of 1-100 mg/mL. Some examples of dosages are 1 mg/mL, 10 mg/mL, 25 mg/mL, 50 mg/mL, and 100 mg/mL. Generally, other agents will be present in a unit range similar to agents of that class used clinically. Typically, this is 1-100 mg/mL.

The invention encompasses all conventional modes of administration; oral and parenteral methods are preferred. Generally, the dosing regimen will be similar to other agents used clinically. Typically, the daily dose will be 1-100 mg/kg body weight daily. Generally, more compound is required orally and less parenterally. The specific dosing regime, however, will be determined by a physician using sound medical judgement.

To a solution of diisopropylamine (19.7 mL, 138 mmol) in tetrahydrofuran (50 mL) at -78° C. was added nBuLi (2.5 M in hexane, 55.8 mL, 140 mmol) dropwise. The reaction was allowed to gradually warm in the bath to -30° C., held there for 5 min, and re-cooled to -78° C. The reaction was treated with 2-(3-bromophenyl)acetic acid (15 g, 70 mmol) in tetrahydrofuran (200 mL) over 10 minutes. The ice bath was removed and stirring continued for 1.5 h. The reaction was cooled to 0° C., and treated with a solution of 3-methoxybenzaldehyde (8.49 mL, 69.8 mmol) in tetrahydrofuran (50 mL). The reaction was allowed to gradually warm to room temperature overnight. The reaction was poured onto ice water and extracted with diethyl ether. The ethereal was discarded. The aqueous layer was acidified by addition of concentrated hydrochloric acid at 0° C. until it was very acidic. The product was extracted with diethyl ether (3x). The ethereal was washed with brine, dried over magnesium sulfate, and concentrated to give 24.8 g (83%) as a colorless viscous gum as a racemic mixture of diastereomers which was used without purification. To diisopropylamine (0.241 mL, 1.693 mmol) in tetrahydrofuran (10 mL) under nitrogen at -78° C . was added n-BuLi (0.677 mL, 1.693 mmol). After 60 min, the colorless solution was warmed to -20° C . and a solution of 2-(3-(phenylethynyl)phenyl)acetic acid (200 mg, 0.847 mmol; Araldi, G. L.; Liao, Y.; Brugger, N. Hydrazide Derivatives as Prostaglandin Receptor Modulators. WO 2005/012232 A2, 2005) in tetrahydrofuran (5 mL) was added resulting in a red solution which was allowed to stir for 45 min as the cooling bath temperature rose to 5° C . The reaction was recooled to -30° C ., benzaldehyde (0.103 mL, 1.016 mmol) was added dropwise resulting in immediate disappearance of the red color and the cooling bath was removed. After 48 h, the reaction mixture was quenched with 1N HCl (20 mL), extracted with ethyl acetate (3 $\times$ 20 mL), washed with brine, dried over MgSO_4 , filtered and concentrated providing (2S,3R)-3-hydroxy-3-phenyl-2-(3-(phenylethynyl)phenyl)propanoic acid as an amber oil which was used in the next step without further purification or characterization.

To (2S,3R)-3-hydroxy-3-phenyl-2-(3-(phenylethynyl)phenyl)propanoic acid (290 mg, 0.847 mmol) in Toluene (10 mL) was added Hunig'sBase (0.192 mL, 1.101 mmol) followed by diphenyl phosphorazidate (0.183 mL, 0.847 mmol). The reaction mixture was heated to 60° C . for 18 h and an add'l portion of diphenyl phosphorazidate (0.183 mL, 0.847 mmol) was added with continued heating. After 1 h, the reaction was cooled and concentrated to 3 mL volume and applied to 12 g silica gel cartridge which was

pre-equilibrated with 5% ethyl acetate/hexanes. Elution with 5 to 40% ethyl acetate/hexanes over 300 mL provided 179 mg racemic trans-5-phenyl-4-(3-(phenylethynyl)phenyl)oxazolidin-2-one which was rechromatographed under identical conditions providing 79 mg racemic trans-5-phenyl-4-(3-(phenylethynyl)phenyl)oxazolidin-2-one as a colorless oil. The enantiomers were separated via chiral preparative HPLC (Preparative HPLC Method 2) in two portions solubilizing in 1:1 $\text{CH}_2\text{Cl}_2/\text{MeOH}$ providing 36 mg (12%) (4R,5R)-5-phenyl-4-(3-(phenylethynyl)phenyl)oxazolidin-2-one (enantiomer 1; Retention time=8.48 min) and 35 mg (12%) (4S,5S)-5-phenyl-4-(3-(phenylethynyl)phenyl)oxazolidin-2-one (enantiomer 2; Retention time=16.36 min) ^1H NMR (500 MHz, CHLOROFORM-d) δ ppm 7.48-7.58 (4H, m), 7.28-7.45 (9H, m), 7.22-7.28 (1H, m), 5.32 (2H, d, $J=7.32$ Hz), 4.75 (1H, d, $J=7.32$ Hz). (4S,5S)-5-phenyl-4-(3-(phenylethynyl)phenyl)oxazolidin-2-one and (4S,5R)-5-phenyl-4-(3-(phenylethynyl)phenyl)oxazolidin-2-one

To (S)-tert-butyl 2-hydroxy-1-(3-(phenylethynyl)phenyl)ethylcarbamate (100 mg, 0.296 mmol) in dichloromethane (2 mL) was added sodium bicarbonate (124 mg, 1.482 mmol) followed by Dess-Martin Periodinane (151 mg, 0.356 mmol). After 1 h, the reaction was quenched with 1:1 saturated $\text{NaHCO}_3/\text{Na}_2\text{SO}_3$ and extracted into ethyl acetate (10 mL). The organic layer was dried with MgSO_4 , filtered and concentrated to 96 mg (S)-tert-butyl 2-oxo-1-(3-(phe-

nylithynyl)phenyl)ethylcarbamate as an amber oil which was concentrated from toluene under high vacuum and used directly in the next step without further purification. $R_f = 0.5$ (silica gel, 25% ethyl acetate/hexane, UV and phosphomolybdc acid).

To (S)-tert-butyl 2-oxo-1-(3-(phenylethynyl)phenyl)ethylcarbamate (95 mg, 0.283 mmol) in tetrahydrofuran (5 mL) at -78°C . was added phenylmagnesium bromide (0.198 mL, 0.595 mmol) dropwise. After half of the phenylmagnesium bromide was added the stir bar stopped spinning due to a gum which formed around it. The ice bath was removed allowing the reaction to warm until the stir bar began to stir again. The addition of Grignard reagent was continued and after 1 h, a fine precipitate was evident. TLC (25% ethyl acetate/hexane; UV and phosphomolybdc acid) showed a single major spot just below starting material ($R_f = 0.45$). After 1.5 h total, the reaction was quenched with 1N HCl (10 mL) and extracted into ethyl acetate (3 $\times$ 10 mL). The combined organics were washed with saturated NaHCO_3 , brine, dried over MgSO_4 , filtered and concentrated in vacuo to 126 mg amber oil which was loaded with dichloromethane onto a 12 g silica gel column prepakced with 5% ethyl acetate/hexanes. Elution with 5 to 30% ethyl acetate/hexanes over 250 mL provided 62 mg tert-butyl (1S,2S)-2-hydroxy-2-phenyl-1-(3-(phenylethynyl)phenyl)ethylcarbamate as a colorless oil which was used directly in the next step.

To (S)-tert-butyl 2-hydroxy-2-phenyl-1-(3-(phenylethynyl)phenyl)ethylcarbamate (62 mg, 0.150 mmol) in tetrahy-

drofuran (3 mL) at -78°C . was added NaH (17.99 mg, 0.450 mmol). After 10 min, the ice bath was removed and the reaction was allowed to stir at ambient temperature for 24 h at which time TLC showed two spots at $R_f = 0.2$ and $R_f = 0.15$ (25% ethyl acetate/hexanes, UV) with the top one as major. The reaction was quenched with 1N HCl (15 mL), extracted into ethyl acetate (3 $\times$ 20 mL), washed with saturated NaHCO_3 , brine, dried over MgSO_4 , filtered, and concentrated to 51 mg colorless solid which was dissolved in dichloromethane and applied to a 12 g silica gel cartridge prepakced with 5% ethyl acetate/hexanes. Elution with 5 to 40% ethyl acetate/hexanes over 300 mL provided 29 mg (57%) (4S,5S)-5-phenyl-4-(3-(phenylethynyl)phenyl)oxazolidin-2-one as a colorless oil (top spot) and 5 mg (11%) (4S,5R)-5-phenyl-4-(3-(phenylethynyl)phenyl)oxazolidin-2-one as a colorless solid. To trans-4-(3-bromophenyl)-5-(pyridin-3-yl)oxazolidin-2-one (46 mg, 0.144 mmol) slurred in triethylamine (3 mL) was added ethynylbenzene (0.021 mL, 0.187 mmol), copper (I) iodide (2.74 mg, 0.014 mmol), and triphenylphosphine (26.5 mg, 0.101 mmol). The reaction mixture was cooled to -78° C. under nitrogen and subjected to three rounds of pump/nitrogen purge. (4R,5R)-5-(2,5-difluorophenyl)-4-(5-(phenylethynyl)pyridin-3-yl)oxazolidin-2-one

To a stirred solution of optically enriched (4R,5R)-4-(5-bromopyridin-3-yl)-5-(2,5-difluorophenyl)oxazolidin-2-one (1.25 g, 3.25 mmol) in triethylamine (70 mL) was added ethynylbenzene (0.592 mL, 5.28 mmol), copper(I) iodide (67 mg, 0.352 mmol), and triphenylphosphine (653 mg, 2.464 mmol). Nitrogen was bubbled through the mixture for 10 minutes before adding dichlorobis(triphenylphosphine)-palladium(II) (202 mg, 0.282 mmol) with continued nitrogen gas bubbling. After an additional 10 minutes the reaction

20 mixture was heated to reflux for 16 hours, cooled to ambient temperature, diluted with EtOAc, washed with water (3×), brine, dried over magnesium sulfate, and concentrated in vacuo. Column chromatography (25%->40% EtOAc/Hex) provided optically enriched (4R,5R)-5-(2,5-difluorophenyl)-4-(5-(phenylethynyl)pyridin-3-yl)oxazolidin-2-one 25 which was separated by chiral SFC chromatography (Chiralcel OJ-H preparative column, 30×250 mm, 5 μm, Mobile Phase: 40% MeOH (0.1% DEA) in CO₂ @ 150 Bar, Temp: 35° C., Flow rate: 70.0 mL/min. for 16 min, UV monitored @ 280 nM. t_R=9.23 min) to provide (1.38 g, 2.99 mmol, 30 85% yield) of pure single enantiomer (4R,5R)-5-(2,5-difluorophenyl)-4-(5-(phenylethynyl)pyridin-3-yl)oxazolidin-2-one. ¹H NMR (500 MHz, DMSO-d₆) δ ppm 8.77 (d, J=2.21 Hz, 1H) 8.57 (s, 1H) 8.56 (d, J=2.20 Hz, 1H) 8.07 (t, J=2.05 Hz, 1H) 7.58-7.66 (m, 2H) 7.44-7.52 (m, 3H) 7.39-7.45 (m, 1H) 7.28-7.39 (m, 2H) 5.67 (d, J=6.62 Hz, 1H) 5.04 (d, J=6.62 Hz, 1H). ¹³C NMR (126 MHz, DMSO-d₆) δ ppm 157.28; 157.24 (d, J=240.70 Hz) 155.92 (d, J=245.20 Hz) 151.63; 147.70; 136.78; 135.02; 131.57; 129.43; 128.89; 126.63 (dd, J=14.99, 7.72 Hz) 121.51; 119.47; 117.83 (dd, J=23.60, 9.10 Hz) 117.50 (dd, J=24.50, 8.20 Hz); 114.60 (dd, J=26.34, 4.54 Hz); 92.86; 85.76; 78.12; 59.43; LCMS (ESI) m/z calcd for C₂₂H₁₅F₂N₂O₂: 377.11. found 377.20 [M+H]⁺; HRMS (ESI) m/z calcd for C₂₂H₁₅F₂N₂O₂: 377.1096. found 377.1096 [M+H]⁺.

A flask was charged with N-(diphenylmethylene)-1-(5-(phenylethynyl)pyridin-3-yl)methanamine (0.21 g/mL in toluene, 1.5 mL, 0.85 mmol) and concentrated. The residue was dissolved in tetrahydrofuran (5.5 mL), and cooled to -78° C. To this was added t-BuLi (1.7M in pentane, 0.60 mL, 1.02 mmol) dropwise. After 20 min, the resulting solution was treated with pyrimidine-4-carbaldehyde (91 mg, 0.85 mmol). After stirring at -78° C. for 10 min, the

reaction was allowed to gradually warm to room temperature in the bath. The reaction was diluted with ether, quenched by addition of water, and warmed to room temperature with stirring. The layers were separated. The organics were washed with brine and concentrated to give a gummy solid. The crude product was dissolved in methanol (6 mL) and treated with methoxyamine hydrochloride (212 mg, 2.54 mmol). The reaction was stirred at room temperature overnight. The reaction was concentrated, dissolved in methanol, and loaded on a medium cation exchange cartridge (6 g cartridge). The cartridge was flushed with several volumes of methanol which were discarded. The product was eluted with 2M ammonia in methanol and concentrated to afford 277 mg as an orange gum. The crude amino alcohol was dissolved in tetrahydrofuran (5 mL), cooled to 0° C., and treated with carbonyldiimidazole (149 mg, 0.919 mmol). The ice bath was removed and stirring continued overnight. The material was purified by prep HPLC (Sunfire Column, TFA/MeOH) to isolate the two major fractions (F1=first to elute, F2=second to elute).
